(57) **CLAIM**

The ornamental design for a downspout extension, as shown and described.

DESCRIPTION

FIG. 1 is a front, top perspective view of a downspout extension, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and
FIG. 8 is a bottom plan view thereof;
FIG. 9 is an enlarged perspective view of detail "9" identified in FIG. 1;
FIG. 10 is an enlarged perspective view of detail "10" identified in FIG. 1;
FIG. 11 is an enlarged perspective view of detail "11" identified in FIG. 2;
FIG. 12 is an enlarged perspective view of detail "12" identified in FIG. 2;
FIG. 13 is an exploded view of FIG. 1;
FIG. 14 is an exploded view of FIG. 2;
FIG. 15 is an exploded view of FIG. 3;
FIG. 16 is an exploded view of FIG. 4;
FIG. 17 is an exploded view of FIG. 5;
FIG. 18 is an exploded view of FIG. 6;
FIG. 19 is an enlarged perspective view of detail "19" identified in FIG. 13;
FIG. 20 is an enlarged perspective view of detail "20" identified in FIG. 14;
FIG. 21 is a perspective view thereof, shown in an alternative position; and,
FIG. 22 is another perspective view thereof, shown in an alternative position.

The dashed lines in the figures illustrate portions of the downspout extension that form no part of the claimed design. The dash dot dash lines in FIGS. 1, 2, 9, 10, 11, 12,

(Continued)

13, 14, 19 and 20 are for the purpose of illustrating the enlarged views indicators and form no part of the claimed design.
